US00D861759S

(12) **United States Design Patent** (10) Patent No.: **US D861,759 S**
 Bloom et al. (45) Date of Patent: ** Oct. 1, 2019

(54) **BEZEL**

- (71) Applicant: **Graco Minnesota Inc.**, Minneapolis, MN (US)
- (72) Inventors: **Michael E. Bloom**, Anoka, MN (US); **Joshua R. Holmstadt**, St. Michael, MN (US); **Bradley G. Kahler**, Otsego, MN (US); **Benjamin J. Paar**, Minneapolis, MN (US); **Anthony J. Kuschel**, Coon Rapids, MN (US); **James R. Ebbin**, Shoreview, MN (US); **Shane A. Norman**, Oak Grove, MN (US)
- (73) Assignee: **Graco Minnesota Inc.**, Minneapolis, MN (US)
- (**) Term: **15 Years**
- (21) Appl. No.: **29/658,038**
- (22) Filed: **Jul. 27, 2018**

(Continued)*Primary Examiner* — Patricia A Palasik(74) *Attorney, Agent, or Firm* — Kyle B. Liudahl(57) **CLAIM**

The ornamental design for a bezel, as shown and described.

DESCRIPTION

FIG. 1 is a perspective view of a bezel;
 FIG. 2 is a front view thereof,
 FIG. 3 is a rear side view thereof,
 FIG. 4 is a right side view thereof,
 FIG. 5 is a left side view thereof;
 FIG. 6 is a top view thereof; and,
 FIG. 7 is a bottom view of a bezel.

The broken lines are indicative of an unclaimed portion of the design.

1 Claim, 4 Drawing Sheets(56)
